A. S. RICHARDSON.
AIR SHAFT FOR MINES.
APPLICATION FILED DEC. 24, 1919.

1,381,017.

Patented June 7, 1921.

UNITED STATES PATENT OFFICE.

ALLAN S. RICHARDSON, OF BUTTE, MONTANA.

AIR-SHAFT FOR MINES.

1,381,017.

Specification of Letters Patent. Patented June 7, 1921.

Application filed December 24, 1919. Serial No. 347,058.

To all whom it may concern:

Be it known that I, ALLAN S. RICHARDSON, a citizen of the United States, residing at Butte, in the county of Silverbow and

5 State of Montana, have invented certain new and useful Improvements in Air-Shafts for Mines, of which the following is a specification.

The present invention relates to mine 10 shafts and particularly to air shafts.

It is the principal object of the invention to make provisions to increase the air carrying capacity of the shafts and also for protection of shaft timbers against fire.

15 The invention, in its broader aspect, consists in smooth-surfacing air shafts.

In its more specific aspect the invention consists in molded plates or slabs and auxiliary molded connecting links between the 20 slabs and the shaft timbers for smooth-surfacing shafts in a simple and effective manner.

For a fuller understanding of the invention reference is had to the appended drawings in which—

Figure 1 is a plan view of the usual main shaft timbers;

Fig. 2 is a section on line 2—2, Fig. 1 showing how the invention is applied;

30 Fig. 3 is a similar view taken on line 3—3, Fig. 1;

Fig. 4^a is a cross sectional view of the usual wall plate;

Fig. 4^b is a similar view showing a wall 35 plate piece attached thereto according to the invention;

Fig. 5 is a perspective view of a wall plate piece, and

40 Figs. 6^a and 6^b are front and rear views respectively of a slab.

In Fig. 1, 1 represents wall plates running from one end of the shaft to the other, 2 the end plates interconnecting the wall plates 1 at the ends thereof and 3 center plates by 45 which the shaft may be divided in a plurality of compartments or shaft sections. Vertical timbers 4 rest on the wall plates and support another set of wall plates which in turn support other vertical timbers or posts. 50 The structure represented illustrates the usual shaft structure to which my invention is to be applied.

To carry out the object of my invention I use principally two structural elements, 55 namely a wall plate piece 5 and a slab 6, both made of mortar or concrete. The wall

plate pieces 5 are set upon the wall plates 1, the end plates and the center plates and form the bases for the slabs 6 to rest upon.

In shafts which have been in use for some 60 time, the edges of the horizontal timbers or plates are often badly cut by falling rock as indicated in Fig. 4^a. In order to properly set the angular pieces or wall plate pieces 5 upon the wall plates, it is necessary to apply 65 to the latter an even bed of mortar. I also cut notches 9 in the upper surface of the plates 1, 2 and 3 and fill these notches with mortar or cement. Upon the timber thus preliminarily treated I set the angular wall 70 plate piece 5. While there is of course considerable latitude in the selection of means for securely locking the pieces 5 to the timbers, I prefer to form a plurality of holes 7 in the horizontal portion and when it is in 75 proper position upon the timber, I fill these holes with mortar, cement or concrete. When the mortar sets, the pins thus formed pass through the wall plate pieces into the timber and securely hold them in place. 80

The slabs are preferably provided with flanges 6' at the top and the bottom which together with vertical ribs 6'' extending along the rear surface stiffen the slab and also afford means for setting it in place. 85 After the wall plate pieces 5 are put in place, the slabs are set so that at the lower end the flanges rest directly on them, the smooth surface being set outward toward the shaft. Wooden wedges 8 are then driven in between the top of the slab and the bottom of the wall plate above it. In this manner the slabs are securely held in place. When all the slabs in a given compartment are thus set in place, they are pointed-up with cement 90 or mortar to produce a continuous smooth surface throughout the compartment. It is understood that prior to the finishing touches the projecting portions of the wedges are cut off flush with the surface of the slab. 100

The particular mode of securing the slabs in place has been referred to because it is exceedingly simple and satisfactory. However, various other methods and means are applicable within the scope of the invention. 105

Fig. 3 shows the invention applied to the central winding shaft section. The guides 10 for the cage are fastened by lag screws to the center plates 3 and after the slabs 6 are set in place at both sides of the guides 110 10, the exposed surface is finished as previously described.

I claim:

1. The combination with the horizontal timbers of a mine shaft of angular pieces of fire-proof material adapted to rest upon the 5 horizontal timbers and extend over the front surfaces thereof, means for securing the said pieces to the timbers, slabs of fire-proof material formed to extend from the upper surfaces of the angular pieces on one set of 10 horizontal timbers to the lower surfaces of the next higher set of horizontal timbers and means for securing the slabs in position.

2. The method of smooth-surfacing mine-shafts which consists in securing to the horizontal timbers thereof angular pieces of cementitious material resting on the upper surface of the timbers and covering the front surface thereof and securing between the 20 upper surfaces of said angular pieces and the lower surface of the next set of horizontal timbers slabs of cementitious material.

3. The method of smooth-surfacing mine-shafts which consists in securing to the horizontal timbers thereof angular pieces of cementitious material resting on the upper surface of the timbers and covering the front surface thereof, securing between the upper surfaces of said angular pieces and 30 the lower surface of the next set of hori-

zontal timbers slabs of cementitious material and filling the interstices with cementitious material.

4. The method of smooth-surfacing mine-shafts which consists in securing to the horizontal timbers thereof angular pieces of cementitious material resting on the upper surface of the timbers and covering the front surface thereof, wedging slabs of cementitious material between the upper surfaces 40 of said angular pieces and the lower surface of the next set of horizontal timbers, removing the projecting portions of the wedges and filling the interstices with cementitious material.

5. The step in the method of smooth-surfacing mine-shafts which consists in notching the upper surface of the horizontal timbers, applying an even bed of cementitious material thereto, uniting with said bed angular pieces of cementitious material extending over the front surface of said timbers and supporting slabs on the upper surface of said angular pieces.

In testimony whereof I affix my signature 55 in presence of two witnesses.

ALLAN S. RICHARDSON.
